AUTOMATIC FIRE SPRINKLER SYSTEM

Filed July 2, 1925

UNITED STATES PATENT OFFICE.

HENRY M. MINNIS, OF WYLIE, TEXAS, ASSIGNOR OF ONE-THIRD TO ELBA A. THOMAS
AND ONE-THIRD TO JOHN H. FINCH, BOTH OF WYLIE, TEXAS.

AUTOMATIC FIRE SPRINKLER SYSTEM.

Application filed July 2, 1925. Serial No. 41,010.

This invention relates to new and useful improvements in valve controlling means for automatic fire sprinkler systems.

The object of the invention is to provide an improved valve operating means controlled by a thermostat disposed in each room to close an electric circuit actuating a trip member to automatically open the water valve of the sprinkler head in said room, thus extinguishing the fire and isolating it at its point of origin.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a detail of the sprinkler valve and its operating means.

Fig. 2 is a plan view of the same,

Fig. 3 is a cross sectional view of the sprinkler valve.

The parts shown in the drawing are adapted to be associated with any desired source of water supply and the discharge valve is controlled by electrical connections from a battery and thermostat of the usual type.

In each room the sprinkler pipe 14 has at its upper end a valve 16 and a sprinkler head 15 at its lower end. The valve has a swinging gate 17 operated by a rock shaft 18, Figs. 1 and 3, but the particular type of valve may be varied.

When the gate is down the valve is closed. For swinging the valve a lever 19 is attached at one end to the rock shaft and has its other end loosely connected with an arm 20.

For supporting the arm in an elevated position so as to normally close the valve a rock shaft 21 is hinged on a plate 22 suspended or supported by brackets 23. The shaft 21 has a trip lug 24 on one end and the upper end of the arm is notched to engage over said lug.

The arm also engages in a keeper 25 on the edge of the plate, whereby it is held against lateral displacement.

From the opposite end of the shaft 21 a finger 26 extends and has a trip lug 27 at

its free end. A hinged armature plate 28 carries an insulated lip 29 on which the lug 27 rests. A pair of electromagnets 30 are mounted on a bracket 31 on the plate in position to attract the armature when energized. When the plate 28 is swung by the action of the magnets the lip 29 will be swung from under the trip lug 27, whereby the finger 26 will be released to swing down and rock the shaft 21. The shaft 21 upon rocking will swing the lug 24 from the end of the arm 20 which latter will be free to swing down. As the arm swings down it will swing the lever 19 thus rocking the shaft 18 and opening the gate 17. Owing to the loose connection between the arm 20 and the lever 19, the latter will be given a jar when the former swings down. The valves 11 and 16 being opened water will flow through the pipes 10, 12 and 14 and discharge from the sprinkler head 15 in the particular room where the valve 16 is opened.

The electromagnet 30 is connected by wires C and D for the usual thermostatic control and at one side of the plate 22 spaced insulated contacts 33 and 34 are mounted to be engaged by an extension from the armature plate 28. From these contacts lines F and G extend to a suitable signal device to indicate the presence of a fire.

In the operation of the invention a fire in any room will cause the thermostat to close circuit and energize the magnets 30 which attract the armature 28 causing the lip 29 to be swung from under the lug 27 and the finger thus tripped. As the finger swings down the shaft 21 is rocked and the lug 24 withdrawn from its support of the arm 20 which in turn swings downward causing the lever 19 to open the gate 17 of the valve 16.

The invention therefore presents a simple, efficient and economically manufactured controlling device for the sprinkler valve. Various changes in the size and shape of the different parts, as well as modifications and alterations may be made within the scope of the appended claim.

What I claim, is:

A valve controlling means for a fire ex-

100

tinguishing system comprising a pivoted valve, a swinging member extended from the pivot thereof, a base, a rock shaft having a horizontally disposed portion pivoted thereon and formed with a supporting lug at one side of the base to lie beneath said member and an elongated gravity finger at

the opposite side of the base, a magnet upon the base, and a cooperating armature having a shoulder upon its outer face beyond 10 the side of the base to support said finger and swinging member in elevated position.

In testimony whereof I affix my signature.
HENRY M. MINNIS.
